UNITED STATES PATENT OFFICE.

WILLIAM J. CAMERON, OF CHICAGO, ILLINOIS.

ATTACHMENT FOR RETRACTORS.

1,238,001.

Specification of Letters Patent. Patented Aug. 21, 1917.

Application filed May 28, 1915. Serial No. 30,899.

To all whom it may concern:

Be it known that I, WILLIAM J. CAMERON, a subject of the King of Great Britain, having declared his intention of becoming a 5 citizen of the United States, and a resident of the city of Chicago, county of Cook, and State of Illinois, have invented certain new and useful Improvements in Attachments for Retractors, of which the following is a 10 specification.

My invention relates to surgical retractors. More particularly stated my device is an attachment for retractors adapted for use by dentists, or mouth and throat specialists, for the purpose of depressing the tongue of a patient or for spacing the fleshy portion of the cheek away from the gums and teeth, and for holding absorbent cotton roll close to the gums of the patient. 15 The principal object of my invention is the provision of a suitable attachment that may be readily and quickly secured to a retractor or gag and held in position without the use of set screws or similar locking means. An 20 other object of my invention is to so construct the attachment that when employed by a dentist or other operative it will provide a clear working space around the gums and teeth of a patient and at the same time 25 permit of the drainage of saliva therefrom. Other objects are the provision of an attachment that may be used in a patient's mouth without discomfort, is secured to the retractor or gag without altering the same, 30 and which is economical to manufacture so that it may be retailed at a moderate price.

I prefer to accomplish these and other objects by the means and in the manner hereinafter fully described and as more particularly pointed out in the claims, reference 40 being had to the accompanying drawings forming a part of this specification, wherein,

Figure 1 is a perspective view of my invention.

Fig. 2 is a top plan of the tongue depressor roll holder and cheek distender or cotton roll holder for the lower jaw and detached from the retractor.

Fig. 3 is a plan of the cheek distender for 50 the upper jaw and detached from the retractor. Fig. 4 is a tongue depressor for use in throat examination and diagnosis.

Fig. 5 is a side elevation of the structure illustrated in Fig. 4.

55 Referring to the drawings, similar ref-

erence characters are employed to indicate the same parts in the several views.

As illustrated in the drawings, it will be seen the retractor or gag preferably comprises a main member 5 of substantially L 60 or U shape and an adjustable member 6 adapted to engage the same and slide longitudinally thereon by means of the inturned lips 7 that provide a guide. The main member 5 has its arm 8 disposed substantially at 65 right angles thereto and slightly convexed, the end thereof bent over to form a downward hook 9.

The movable or slid able member 6 has its arm 10 also disposed at substantially right 70 angles to itself and slightly convexed to conform to the shape of the arm 8, while the outer end thereof is bent upwardly, which bend is provided to form a hook 11. In using this device as a mouth gag the hooks are placed 75 against the teeth in the upper and lower jaws and when the jaws are moved apart, the operator will spread the arms away from each other, causing member 6 to slide upon the main member 5. The tendency of the 80 jaws to then come together causes the movable member to shift to one side and frictionally lock the guide 7 upon the member 5. The structure heretofore described is substantially the same as that described and 85 illustrated in Letters Patent No. 955,006 granted to J. E. Sparks, April 12, 1910 for abdominal retractor, whereof I am owner, and to which my improved attachment is 90 adapted to be applied.

Referring first to Fig. 4 in the drawings, wherein the tongue depressor of a simple type is shown, it will be observed the depressor comprises a plate 12 of suitable dimensions and shape that is bent substantially 95 in the manner shown in Fig. 5 of the drawings. This plate 12 is provided at its upper end with substantially L-shaped retaining lugs 13 that arise from the sides thereof and immediately adjoining said lugs 100 is a portion 14 bent in a substantially quadrant shape curve, so that it corresponds with the curvature and fits the hooks 9 and 11 of the mouth gag. The plate is then bent upwardly a slight distance then flat to form 105 a corner 15 in order that, when the instrument is placed in the mouth of the patient, the teeth will rest upon the curved portion 14 and the body of the plate 12 will rest upon and depress the tongue. In order to 110

retain the plate upon the hooks and prevent the same moving too far backward, suitable shoulders 9^a and 11^a are made upon the edges of the respective hooks.

5 In Figs. 1 and 2 of the drawings, I have illustrated a differently shaped tongue depressor 16, one longitudinal edge 17 whereof is bent or flared downwardly and upwardly as shown, and adjacent the upper end of plate 16 is a restricted throat 18. One side edge of the throat is turned upwardly to form a rib or flange 19 of substantially segmental shape, and beyond the throat 18 the plate is bent in a curve 20 to conform to the curvature of the hook 9. At its end the sides of the plate is provided with substantially L-shaped lugs 21 for engaging the edges of said hooks when the device is in position. A lateral extension 22 projects from the curved portion 20 of the plate and adjacent its end is provided with an upturned lip 23 that is adapted to contact the gum of the patient when the device is inserted in the mouth. The device just described is adapted to be placed upon the lower hook 9 of the mouth gag, and when placed in the mouth of the patient will force the tongue and cheek away from the lingual and labial sides of the gums so as to provide a clear working space 30 for the operator.

For the purpose of permitting operations in the upper jaw of the patient I have devised the structure illustrated in Fig. 3 of the drawings, which is substantially the same as the extension member 22 illustrated in Fig. 2 with the plate 16 omitted. A down-turned lip 24 at the outer end of the extension 25 is provided that is bent in the opposite direction to lip 23 so that the device may 40 be used at the labial side of the upper jaw.

The curved portion 20 and the L-shaped lugs 21 are the same as illustrated upon the other attachments heretofore described.

While I have herein illustrated and described certain specific means for carrying out my invention, it of course, will be obvious, to others skilled in the art to which it pertains, that various modifications or refinements thereof are possible without materially departing from the spirit of my invention. I therefore desire it understood that all such changes are contemplated with the scope of my invention as expressed in the appended claims.

55 What I claim as new and desire to secure by Letters Patent is:—

1. A surgical retractor comprising arms provided with carrying means adjacent their outer ends, means whereby said arms are retained in adjusted positions, and a suitably shaped plate adapted to coöperate with said carrying means whereby said plate is removably mounted upon one of said arms.

2. A surgical instrument comprising separate arms having hooks upon their outer ends, means connecting said arms whereby said arms are retained in adjusted positions, and a suitably shaped plate removably mounted upon one of said hooks. 65

3. A surgical instrument comprising separable arms having hooks upon their outer end, means adjustably connecting said arms and a suitably shaped plate adapted to be mounted upon one of said hooks and provided with lateral substantially L-shaped 75 lugs that embrace the edges of said hook.

4. A surgical instrument comprising separable arms having hooks upon their outer ends, means adjustably connecting said arms, and a suitably shaped plate adapted to be 80 mounted upon one of said hooks, said plate provided with a segmentally curved portion adapted to fit said hook and lateral substantially L-shaped lugs that embrace the edges of said hook. 85

5. An attachment for a retractor comprising a suitably shaped member, an extended arm disposed adjacent to and along side said member and providing a space therebetween, and a restricted throat portion for 90 said member adjacent the point of projection of said arm.

6. An attachment for a retractor comprising a suitably shaped member and extended arm disposed adjacent to and along side said member and providing a space therebetween, and means whereby said member is mounted upon the retractor consisting of a segmentally curved portion adjacent one end thereof, and substantially L-shaped lugs adjacent said curved portion. 95 100

7. An attachment for a retractor comprising a suitably shaped member, an extended arm disposed adjacent said member and providing a space therebetween, said arm having a laterally bent lip, and a restricted throat portion adjacent the point of projection of said arm. 105

8. A surgical retractor comprising separate arms the ends whereof are suitably shaped, means whereby said arms are frictionally retained in adjusted positions and a plate removably mounted upon the end of one of said arms. 110

9. A surgical retractor comprising two members slidably and frictionally connected together the opposite ends whereof are suitably shaped and a plate removably mounted upon the end of one of said members. 115

Signed at Chicago, Cook county, Illinois, 120 this 26 day of May 1915.

WILLIAM J. CAMERON.
